(57) **CLAIM**

The ornamental design for a light fitting, as shown and described.

DESCRIPTION

FIG. 1 is an isometric view showing a first embodiment of a light fitting showing the design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is an isometric view showing a second embodiment of a light fitting showing the design.

FIG. 8 is a front elevation view thereof.

FIG. 9 is a rear elevation view thereof.

FIG. 10 is a left side elevation view thereof.

FIG. 11 is a right side elevation view thereof; and,

FIG. 12 is a top plan view thereof.

The dashed lines shown in the drawings indicate portions of the light fitting that form no part of the claimed design. The dash-dot lines shown in the drawings indicate a boundary line separating claimed and unclaimed portions of the design, with the claimed subject matter extending to the dash-dot boundary line but not including the dash-dot boundary line.
